UNITED STATES PATENT OFFICE.

GEORGE W. MCGILL, OF NEW YORK, N. Y.

DESIGN FOR A FASTENER FOR PAPERS.

SPECIFICATION forming part of Design No. 19,220, dated July 23, 1889.

Application filed June 26, 1889. Serial No. 315,642. Term of patent 14 years.

To all whom it may concern:

Be it known that I, GEORGE W. MCGILL, a citizen of the United States, residing at Riverdale, New York, in the county of New York and State of New York, have invented and produced a new and original Design for a Fastener for Papers, of which the following is a specification.

This design has for its object to provide a novel fastener for papers; and the leading feature thereof consists in a flat prong having a flat cross-head extending at right angles to the prong and lying in the plane of the latter.

The design is illustrated by the accompanying drawings, in which—

Figure 1 is a perspective view looking at the front side of the fastener. Fig. 2 is a similar view looking at the adhesive rear side thereof, and Fig. 3 is an edge view of the same.

The numeral 1 indicates the flat prong, and 2 the flat cross-head extending from the prong

at right angles thereto and forming a T-shaped fastener. The cross-head and the 25 prong have their opposite sides or faces in the same plane, respectively, and as here shown the end of the prong is pointed, as at 3, while the ends of the cross-head are convex, as at 4. The outer and inner edges 5 30 and 6 of the cross-head are shown as parallel, and the inner edges 6 are at right angles to the edges 7 of the prong.

What I claim is—

The design for a fastener for papers, consisting of the flat prong 1, having the flat cross-head 2 extending at right angles to the prong and lying in the plane of the latter, substantially as shown and described.

In testimony whereof I have affixed my signature in presence of two witnesses.

GEORGE W. MCGILL.
